UNITED STATES PATENT OFFICE.

SWITS CONDÉ, OF OSWEGO, NEW YORK.

DESIGN FOR A KNIT FABRIC.

SPECIFICATION forming part of Design No. 12,760, dated February 14, 1882.

Application filed November 7, 1881. Term of patent 7 years.

To all whom it may concern:

Be it known that I, SWITS CONDÉ, of Oswego, in the county of Oswego, in the State of New York, have invented new and useful Improvements in Design for Knit Fabric, of which the following, taken in connection with the accompanying drawing, is a full, clear, and exact description.

This design consists in a novel arrangement 10 of stripes knitted in fabric for underwear.

The design is fully illustrated in the annexed drawing, which represents a piece of fabric embodying my design, the arrangement of the stripes being as follows, to wit: first, a wide 15 mottled stripe, a, then a narrow plain stripe, b, then another wide mottled stripe, a, like the first, then a narrow plain stripe, b, then a narrow mottled stripe, c, then another narrow plain stripe, b, and then again a wide mottled stripe, a, like the first, and so on, 20 the succeeding stripes following in the order aforesaid. All of said stripes are straight and parallel, as shown.

What I claim is—

The design for knit fabric, consisting in the following arrangement of stripes, to wit: first, 25 a wide mottled stripe, a, then a narrow plain stripe, b, then another wide mottled stripe, a, like the first, then a narrow plain stripe, b, then a narrow mottled stripe, c, then another narrow plain stripe, b, and then again a wide 30 mottled stripe, a, like the first, and so on, all of said stripes being straight and parallel, substantially as shown and described.

In testimony whereof I have hereunto signed my name and affixed my seal, in the presence 35 of two attesting witnesses, at Oswego, in the county of Oswego, in the State of New York, this 1st day of November, 1881.

SWITS CONDÉ. [L. S.]
